UNITED STATES PATENT OFFICE.

EMMA HUHN, OF CHICAGO, ILLINOIS.

WINDOW SEAT.

Application filed January 5, 1925. Serial No. 638.

To all whom it may concern:

Be it known that I, EMMA HUHN, a citizen of the United States, residing at Chicago, in the county of Cook and State of Illinois, 5 have invented new and useful Improvements in Window Seats, of which the following is a specification.

This invention relates to window seats especially adapted for use by window 10 washers.

An important aim of this invention is to provide a window chair or seat which may be conveniently secured in a window opening to provide a safe place for a window washer 15 to sit during the washing of the outsides of the upper and lower sashes, the invention providing means whereby both hands of the operator are free for use during the washing of the windows.

20 A further object of the invention is to provide a window chair of the character specified which is of highly simplified construction, simple to adjust, and cheap to manufacture.

25 Other objects and advantages will be apparent during the course of the following description.

In the accompanying drawing forming a part of this application and in which like 30 numerals are employed to designate like parts throughout the same,

Figure 1 is a perspective of the improved window chair in place in a window frame;

Fig. 2 is a perspective of a fastening strip 35 embodied in the invention;

Fig. 3 is a side elevation of the improved window chair;

Fig. 4 is a plan view of the chair in place in the window frame.

40 In the drawings, wherein for the purpose of illustration is shown a preferred embodiment of the invention, the numeral 5 generally designates the seat of the improved chair, which seat consists of a pair of rails 6 to which the panels 7 are connected in any suitable manner.

50 Figs. 1 and 3 illustrate that the front and rear legs 8 and 9, respectively, are rigidly connected to the seat and are joined by cross members 11. Fig. 1 illustrates that the front and rear legs 8 and 9, respectively, are adapted to straddle the window sill 12 and the adjacent portion of the wall 14 and the cross member 11 of the front legs may be provided 55 with feed screws 16 connected at their forward ends as indicated at 18 to a fastening

strip 20. The rear ends of the feed screws 16 are provided with winged heads 22 adapted to be manually turned to force the holding strip 20 firmly into engagement with the 60 adjacent portion of the wall or window sill as the case may be. When the strip 20 is thus forced flatly into contact with the wall or window sill the chair is firmly held in position and cannot accidentally tip or swing 65 out of its proper place in the window frame.

The back generally designated by the numeral 26 consists principally of a pair of spaced parallel inclined rails 28 rigidly secured intermediate their ends to the rear 70 ends of the rails 6 and secured in any suitable manner at their lower ends to the intermediate portions of the rear legs 9. It will be seen with reference to Figs. 1 and 3 that the rails 6 are extended substantial distances 75 beyond the upper portions of the legs 9 and support the rails 28 in an inclined position. The rails 28 are provided with panels 30.

In carrying out the invention the chair is firmly held in position by the strip 20 and 80 by a holding bar 36 adapted to be extended beyond the sides of the window frame and provided with a pair of straps or loops 38, the rear portions of which are extended about the inclined rails 28 and the upper panel 30. 85

In the use of the invention, the chair is first placed in the window frame as illustrated in Fig. 1 and the holding strip 20 is tightened so that the chair is firmly anchored in place. The holding bar 36 is now 90 extended beyond the sides of the window frame and the straps 38 are extended about the bar so as to cooperate with the holding strip 20 in holding the chair in place. Attention is also directed to the fact that the 95 loops 38 also form sides for the chair and thereby prevent the occupant from falling out.

With reference to the foregoing description taken in connection with the accompanying drawing it will be seen that a window washer's seat constructed in accordance with this invention may be conveniently applied to a window of almost any size and when in place will provide a safe supporting means for a window washer. As the loops 100 38 are arranged at both sides and are detachable, they provide a reliable means to hold the chair in place and to prevent the occupant from falling out of the chair sideways. 105

Particular attention is directed to the

fact that the bar 36 is not permanently located at the front of the chair and consequently does not in any way interfere with the ease with which the window washer 5 may enter or leave the chair. The bar 36 is placed in position after the occupant takes his or her seat and is removed before the occupant attempts to leave the seat, the bar being disposed above the knee of the occupant and in position to form a hand grip. 10

Having thus described the invention, what is claimed is:

15 A chair for use by window washers comprising front and rear legs, a seat having horizontal rails rigidly secured to the upper portions of said legs, a back having inclined rails secured to the rear ends of the first-

named rails and to said rear legs, said front and rear legs being adapted to straddle a window frame, flexible loops 20 extended about the upper portions of said second-named rails and forming flexible detachable sides for said chair, and a bar adapted to be passed through the forward portions of said loops and having its ends extended beyond the sides of the window frame at substantially the height of the chair back to hold the chair in position, said loops being located at opposite sides of the chair to prevent the occupant from falling out sideways. 25

In testimony whereof I affix my signature.

EMMA HUHN.
